MULTISTAGE CENTRIFUGAL SEPARATING APPARATUS

Peter Pootjes, Temple City, Calif., assignor to Western Precipitation Corporation, Los Angeles, Calif., a corporation of California

Application August 29, 1941, Serial No. 408,694

5 Claims. (Cl. 209—144)

The present invention relates generally to gas cleaning apparatus of the centrifugal type commonly called "cyclonic separators" wherein a stream of finely divided solid or liquid particles suspended in a stream of gas is subjected to a whirling action to separate the suspended particles from the gas. This invention is more particularly directed to multi-stage separators in which the gas stream is passed through successive separators or stages to obtain a more effective cleaning of the gas.

An object of the invention is to provide a compact multi-stage centrifugal separator with vertically superposed successive separating stages.

Another object of the invention is to provide in a common shell or housing a plurality of vertically superposed centrifugal separating stages.

A further object of the invention is to provide a multi-stage separating apparatus in which successive stages are vertically superposed and are enclosed in a common housing and the housing forms a part of the conduit means for conducting gas between the successive stages.

In ordinary applications it is generally necessary to subject the gas to centrifugal separating action in a relatively small diameter tubular separating device in order to obtain efficient cleaning of the gas. This usually necessitates the employment of a relatively large number of tubes in parallel in each stage in order to handle the large gas volumes encountered in most installations. Accordingly, a particular object of the invention is to provide a compact arrangement of a plurality of centrifugal separating stages, in which one or more of the stages comprise a plurality of relatively small diameter tubes in parallel.

Because of the ease of manufacture and for other obvious reasons, the tubes in the multi-tube units and other gas confining parts thereof are fabricated from relatively lightweight metal, such as thin sheet-metal. In most applications this light construction is perfectly satisfactory since the gas is treated at or near atmospheric pressure and the pressure drop obtained in the separator is usually less than one pound per square inch, so that there is little or no tendency for the apparatus to rupture because of internal pressure. In some applications, however, it is desirable to treat gas at relatively high pressures, for example, pressures in excess of 50 lbs. per square inch. The conventional light-weight construction is entirely unsatisfactory for this purpose and it is commercially impracticable to con-

struct the individual separating units of sufficient weight to stand these pressures.

It is an important object of this invention to provide a multi-stage separating device adapted for treating gases at high pressures in which the individual separating units are of light-weight construction in accordance with the usual practice.

Another important object of the invention is to provide a multi-stage separating device adapted to separate dust efficiently from a gas having a very high dust loading and at high pressure.

How the above objects and advantages of my invention, as well as others not specifically mentioned above, are attained, will be more readily apparent by reference to the following description and the annexed drawings, in which:

Fig. 1 is a vertical sectional view of a three-stage centrifugal separating device according to my invention;

Fig. 2 is a horizontal section through the first stage taken substantially on line 2—2 in Fig. 1;

Fig. 3 is a partly broken away horizontal section through the second stage taken on line 3—3 in Fig. 1;

Fig. 4 is a partly broken away horizontal section through the third stage taken substantially on line 4—4 in Fig. 1;

Fig. 5 is a partial vertical section of a variational form of the device illustrated in Fig. 1, in which the first separating stage comprises a plurality of small diameter tubular separating units;

Fig. 6 is a partial vertical section of another variational form of the invention shown in Fig. 1 in which the second and third stages are provided with involute inlets instead of vane-type inlets as shown in Fig. 1;

Fig. 7 is a horizontal section taken substantially on line 7—7 in Fig. 6 illustrating constructional details of the inlet means; and

Fig. 8 is a sectional detail taken on line 8—8 in Fig. 7;

Referring to Figs. 1 to 4 of the drawings, my multi-stage separating apparatus is shown as comprising a plurality of centrifugal separating stages A, B and C enclosed within a housing 1 which in this form of my invention is shown as an outer cylindrical shell comprising connected and aligned cylindrical intermediate sections 2, 3 and 4 and dome-shaped top and bottom sections 5 and 6 connected to the sections 4 and 2 respectively. Each section of the housing is shown provided with a flange co-operating with the next and the housing sections may be suitably

connected together as by bolting. The sectional construction facilitates fabrication and repair of the apparatus since in some cases the vertical height of the housing 1 may be considerable, for example, from 25 to 50 ft. or more. The several centrifugal separators or separator stages A, B and C are shown as being vertically superposed with respect to each other, that is, they are arranged successively one above another within the housing 1.

The first centrifugal separator at separating stage A is enclosed in the lower portion of the housing 1 and the inner walls of the housing section 2 form part of the first stage. Referring to Figs. 1 and 2 particularly, the housing section 2 is shown provided with a pair of tangential gas inlets 11 and 12 through which the dust-laden gas is introduced to the interior of the housing section 2 which forms the centrifugal separating chamber of that stage, and is caused to swirl about the interior of the housing to centrifugally separate dust particles which are thrown to the housing wall and travel downwardly into a conical hopper 13 communicating through the bottom section 6 with a dust delivery tube 14 through which the collected dust may be transported to a suitable delivery position in a manner well-known in the art. A shield 15 in the form of an inverted truncated cone is shown secured between the housing sections 2 and 3 and extending downwardly into the housing section 2 to a level intermediate the inlet tubes 11 and 12 and is provided at its lower end with a cylindrical shield portion 16 terminating at a level slightly below the inlet tube 12 and concentrically located with respect to the housing portion 2. The cylindrical shield 16 and its upper end 16a comprise the gas outlet tube and gas outlet opening, respectively, for stage A.

The apparatus further comprises a horizontal partition 17 extending across the interior of the housing 1 and secured therein as by fastening between the sections 3 and 4 where they join. The partition 17 defines the upper end of an inlet header compartment 29 for the second stage indicated at B. Within the housing 1 and spaced from the side walls thereof and located at a position spaced vertically below the partition 17 is a housing 21 which encloses and forms part of the second separator at separating stage B. The housing 21 comprises a substantially cylindrical upper portion 22 having a substantially plane wall 23 closing its upper end and defining between it and the partition 17 the inlet header 29 for the second separating stage. The housing 21 is further provided with a bottom portion 24 generally in the form of an inverted truncated cone having at its lower end a dust delivery pipe 25 which extends downward within shield 16 and through the section 2 and out through the bottom section 6 within the dust delivery tube 14 of the first stage. The housing 21 is shown secured in position by means of a plurality of spaced radially extending ribs 26 secured at their inner ends to the housing 21 and at their outer ends to the interior of the shell section 3.

The conical bottom 24 and the flaring shield 15 are spaced from one another to define an outlet header compartment 27 for the first stage communicating with the outlet opening 16a of the first stage. Header 27 communicates with a vertically extending passage 28 defined between side walls 22 and the interior of the shell portion 3, and the upper end of passage 28 communicates with the inlet header 29.

Stage B is shown as comprising a plurality of individual tubular centrifugal separating units 31 connected in parallel. Each centrifugal separating unit comprises a cylindrical tube 32 suspended from wall or partition 23 and open at its upper end 33 to provide gas inlet means for the unit which communicates with the header space 28. The lower end of each unit 31 preferably tapers to a material discharge opening 34 which is in open communication with the interior of the housing 21, the lower portion of which constitutes a material collecting compartment to which delivery pipe 25 is connected. Located coaxially of each unit 31 is gas outlet means provided by tube 35 supported from the partition 17 and communicating with the space in the housing 1 above partition 17 through gas outlet opening 36. The lower end of each tube 35 extends into the upper end of the corresponding tubular unit 31. The tubes 35 and 31 are secured to partitions 17 and 23, respectively, in a gas tight manner.

As may best be seen from Figs. 1 and 3, there is located on the lower end of each outlet tube 35 a ring 37 having thereon a plurality of curved vanes 38 which extend radially from the ring to the inner wall of the unit 32 and are inclined downwardly in one circumferential direction in a generally helical manner. Ring 37 and its attached vanes 38 may be held in place in any suitable manner, as by bolting, for example. These vanes impart to the incoming gas stream the necessary whirling motion to bring about the centrifugal separating action.

A second inner housing 41 is provided within the outer housing or shell 1 above the partition 17, and encloses and forms part of the third separating stage C. The housing 41 comprises vertically extending cylindrical side walls 42 laterally spaced from the inner walls of the shell section 4 to provide therebetween a vertically extending gas passage 43. The housing 41 is provided with a conical bottom portion 44 communicating at its lower end with a dust delivery tube 45 which extends downwardly through partition 17, through the housing 21, and thence through shield 16 and the housing section 2 into the dust delivery tube 14 of stage A alongside of tube 25. The upper end of the housing 41 is closed by a substantially horizontally extending wall or partition 46 which is spaced vertically below a horizontally extending partition 47 extending across the inner housing 1 and held in position therein between the housing sections 4 and 5. The partitions 46 and 47 define therebetween an inlet header space 48 for the separating stage C, the header space communicating with the upwardly extending gas passage 43. The housing 41 is suitably supported in the housing 1 by means of radial arms 49.

Separator or separating stage C is constructed in substantially the same manner as separating stage B and comprises a plurality of tubular separating units 50 suspended from the partition 46 and each having at its upper end an opening 51 providing gas inlet means communicating with the header space 48, and at its lower end or material discharge opening 52 communicating with the interior of the housing 41, the lower portion 70 of the housing 41 indicated at 53 comprising a material collecting compartment for stage C. Each of the separating units also comprises a gas outlet tube 54 depending from the partition 47 and provided with gas outlet opening 55 communicating with a gas outlet header space 56.

defined in the housing between the partition 47 and the top housing section 5. The housing section 5 is shown provided with a gas outlet opening 51 from which clean gas is discharged from the system. The gas outlet tubes 54 extend down part way into the units 50 and each have a plurality of vanes 54a adjacent the lower end thereof for imparting a whirling motion to the gas as described in connection with the vanes 38.

Partition 17 extends completely across the interior of the housing 1 except for the openings therein through which gas outlet pipes 35 and dust delivery tube 45 extend, said partition therefore completely shuts off communication, outside separating stage B, between the gas inlet openings 33 and the gas outlet openings 36 of that stage so that all the gas is required to pass through the separating units of stage B. Similarly, partition 41 extends completely across the interior of housing 1 except for the openings therein through which the outlet tubes 54 extend. Thus partition 41 completely shuts off communication, outside separating stage C, between the gas inlet openings 51 and the gas outlet openings 55, wherefore all the gas is required to pass through the separating units of stage C.

As previously described, gas from stage A passes upwardly from opening 16a into header 21 and thence through vertically extending passage 28 around stage B and within the housing 1 into the inlet header space 29 of stage B; the gas then divides into a plurality of parallel streams which enter the inlet openings 33 of the separating units 31. The gas whirls downwardly in each unit and suspended solids are separated by centrifugal action and are discharged through the openings 34 into the compartment 35. Gas from each unit then passes upwardly through the tube 35 and is discharged through the opening 36 into an outlet header 58 defined within the section 4 between the walls thereof, the conical bottom 44 of the housing 41 and the upper side of the partition 17. The gas streams from the opening 36 are re-united in the header 58 and flow upwardly therein around stage C within the housing 1 to the vertically extending passage 43 communicating therewith and thence to the inlet header 48 of stage C.

The action described in connection with stage B is repeated in stage C, suspended solids being discharged from the openings 52 into the collecting compartment 53 and gas being discharged through the tubes 54 into the outlet header 56.

It will be noted that the outlet header for each lower stage is defined between the partition means adjacent the gas outlet means of the lower stage and the lower portion of the inner housing enclosing the units of the adjacent upper stage. For example, the outlet header of stage A comprising the passage 21 is defined between the shield 15 and the conical bottom 24 of the housing 21. The outlet header of stage B is defined between partition 17 and the conical bottom 44 of the housing 41. In each case the gas outlet means for the lower stage passes through the partition means defining the upper end of the space containing that stage.

The separating units, housings therefor, and partitions, may be of relatively light weight thin-walled construction in accordance with conventional practice. For example, 16-gauge material is often used as it can be readily formed into the desired shape. Light-weight construction provides adequate strength with minimum labor and material costs. Of course, thicker walls are some-

times provided for the separator units when it is desired to provide a longer life in the case of abrasive dusts or corrosive gas constituents. When the gas to be treated is at low pressure, the housing 1 can also be constructed from light-weight material, its design being dictated by purely mechanical requirements.

The illustrated construction is readily adapted to the treatment of gas at high pressure, 50 lbs. per square inch for example, without any change except that of providing the outer housing wall with thick walls adapted to withstand high internal pressures. It is not necessary to increase the thickness of the walls of the parts contained within the housing 1. It will be noted that the partition means and separating units are so arranged that all the compartments and spaces inside and outside of the separating units and stages are subjected to the high pressure of the gas stream. The only pressure difference that exists between parts within the shell or the housing is that which obtains from the normal operation of the device.

In referring to light-weight or conventional construction, reference is made to the thickness of the material used for the separating units and the co-operating inlet and outlet chambers when that thickness is determined independently of the gas pressures as would be the case if the exterior of the units were maintained at atmospheric pressure and the gas stream within the apparatus were substantially at atmospheric pressure. Normally the gas pressure differentials from the walls of the unit are then only those differentials created by the draft necessary for passing gas through the apparatus. Under these circumstances, the thickness of the material used is independent of the gas pressure and is dictated solely by the dead loads of the apparatus and by other considerations, such as rigidity and long life. It will be appreciated that if the walls of the separating unit are made additionally thick in order to resist wear of abrasive dusts, this also may be considered conventional construction, the wall thickness is independent of any gas pressures involved. Even though the separating units may be made of a single integral wall, the situation is strictly analogous to that wherein a thin wall structure is provided with an internal liner which resists the abrasion of the suspended material. It should be appreciated that even though the separating units or other part within my pressure shell are made thicker than is required by considerations of pressure and dead-weight alone, in order to resist wear, eventually the parts will be worn to a relatively thin wall, and might even wear through. Under this latter condition, units of conventional construction would not be capable of containing a gas stream maintained at a relatively high pressure, although it is possible to do so in my novel apparatus wherein the unit walls are not loaded appreciably by gas pressures.

Consequently, although from the standpoint of ability to withstand differences of pressure, only the outer shell need be of heavy pressure-resistant construction and the separating units and interior walls may be of relatively thin construction, it will be understood that it is within the scope of my invention to make the separating units or other interior walls of thick metal for the purpose of resisting wear by abrasive dusts or corrosive gases and prolonging the useful life of the apparatus.

It should be appreciated that the tangential

inlets 11 and 12 may be replaced by a single inlet. However, in constructions of considerable size and where the gas is maintained both at high temperature and high pressure, it is usually advantageous from a practical standpoint to use two smaller inlets instead of one larger one. A separate access opening for each stage is indicated at 59 to facilitate construction and servicing of the apparatus. In order that the parallel delivery tubes 25 and 45 extending through stage A do not disturb the operation, I have provided a cylindrical shield 25a coaxial with the shield 16 enclosing the tubes 25 and 45.

A modified multi-stage construction is illustrated in Fig. 5. This form of my invention is generally comparable to that illustrated in Figs. 1 to 5 except that the first separator or separator stage indicated at D comprises a plurality of small diameter tubes in parallel. The second separator or separator stage E is quite comparable to stage B and the third separator or separator stage F is only partially shown since it may be constructed in the same manner as stage E. In general, stages D and E will comprise a larger number of tubular units than illustrated. In order to avoid the confusion occasioned by showing a larger number of tubular units, only those units in the plane of the view are shown. The stages D, E and F are located within, and spaced inwardly from, a substantially cylindrical outer housing or shell 71 having a conical bottom 72 defining a material discharge compartment 73 for stage E and having a material discharge opening 74 in the lower portion thereof adapted to be closed during operation or connected to a material delivery pipe not shown. The upper portion of the housing 71 may be closed in the same manner as the housing 1 of Fig. 1 and provided with a gas outlet opening. Obviously, other stages besides stage F may be provided above stage E.

Stage D or the first stage comprises a plurality of tubular centrifugal separating units 75 depending from a horizontal partition 76 extending across the interior of the shell 71, the units 75 being secured to the partition 76 in a gas-tight manner. Each of the units has a gas inlet opening 77 at its upper end and a material discharge opening 78 at its lower end communicating with the material collecting compartment 73. The apparatus is further provided with an upper partition 79 in the form of an inverted cone which extends across the interior of the housing 71 and is spaced vertically above the partition 76 to define therebetween an inlet header compartment 81 with which the inlet openings 77 of the separating units communicate. Communicating with the inlet header 81 is gas inlet means 82 in the housing 71.

Each of the tubular separating units is provided with an outlet tube 83 extending into the upper portion of its associated separating unit and provided at its lower end with vanes 84 for imparting the whirling motion to the gas. The upper ends of the outlet tubes extend through the upper partition 79 and communicate through gas outlet openings 86 with outlet header 85 defined in the space above the partition 79.

The second stage E corresponds generally to the second stage B of Fig. 1 and comprises an inner housing 87 having generally cylindrical side-walls 88 spaced laterally or inwardly from the inner side walls of the outer housing 71 to provide therebetween a vertically extending gas passage 89. The housing 87 is provided with a

conical bottom wall 91 defining therewithin a material collecting compartment 92 for stage E. The material collecting compartment 92 is provided at its lower end with a central dust delivery tube 93 which extends downwardly through stage D, passing through partitions 78 and 76 in a gas-tight manner, and then laterally through bottom wall 72 of housing 71.

Bottom wall 91 is spaced vertically from the upper partition 78 and defines therewith and in co-operation with the side-walls of the housing 71 the outlet header 85 for stage D. The outlet header space 85 communicates with the vertically extending gas passage 89 which extends around stage E within the housing 71.

The housing 87 is suitably supported within the housing 71 through the agency of a plurality of radially extending brackets 94. The upper end of the housing 87 is closed by a horizontally extending partition 95 corresponding to the partition 23 of Fig. 1, from which is suspended a plurality of tubular centrifugal separating units 96 comparable to the units 31 of Fig. 1. Each of the units has the material discharge opening 97 communicating with the material collecting compartment 92. Spaced vertically above the partition 95 is an upper partition 98 in the form of an inverted cone extending across the housing 71.

Inlet header or compartment 99 for stage E, communicating with the vertically extending gas passage 89, is defined between the upper partition 98 and the partition 95. Gas inlet opening 101 of each unit 96 communicates with the inlet header 99. Outlet tube 102 of each unit extends through the upper partition 98 and communicates with the space thereabove through outlet opening 103.

Conical bottom portion 104 of stage F, defining outlet compartment 105 therefore, is located within the housing 71 above the partition 98 and is provided with a dust delivery tube 106 which extends downwardly through the partition 98 and thence through the housing 87 concentrically of the outlet or delivery pipe 93 and thence laterally out of the housing 71 through the bottom wall 72. An outlet header 107 is defined between the vertically spaced partitions 98 and 104 for stage E in the same manner that an outlet header 85 is provided for stage D between the vertically spaced partitions 78 and 81. As noted above, the construction of stage F may be similar to that of stage E, with the gas outlet means thereof connected to the above-mentioned gas outlet opening at the top of the housing, in the same manner as shown in Fig. 1.

Partition 79 is located adjacent the gas outlet means of stage D and extends completely across the housing 71 except for the openings therein through which the gas outlet tubes 83 and dust delivery tube 93 extend. Thus said partition completely shuts off communication, outside separating stage D, between the gas inlet openings 77 and gas outlet openings 86 of that stage, causing all the gas to flow through that stage. Similarly, partition 98 is located adjacent the gas outlet means of stage E and extends completely across the housing 71 except for the openings through which the gas outlet tubes 102 and dust delivery pipe 106 extend. Partition 98 completely shuts off communication, outside stage E, between the gas inlet openings 101 and gas outlet openings 103 of that stage, whereby all the gas is caused to pass through that stage.

The operation of this form of my invention is

substantially the same as that described in connection with Fig. 1. Gas enters the housing 71 through opening 82 and flows into inlet header 81 for stage D. The gas then passes in parallel streams through the collecting units 75, separated material being discharged from the discharge opening 78 into the material collecting compartment 73. Gas leaves the separating units 75 through the gas outlet tubes 83 and is discharged through the outlet openings 86 into the outlet header 85. Gas then flows upwardly within the housing 71 and around stage E through the vertically extending gas passage 88 into the inlet header 99 for stage E. The gas then passes in parallel streams through the separating units 96, separated material being discharged through the openings 97 into the material collecting compartment 92. The gas then passes upwardly through the outlet tubes 102 and is discharged through the discharge openings 103 into the outlet header 107 whence it passes into the separating units of stage F from which it may be discharged from housing 71 in the same manner as gas is discharged from the housing 1 of Fig. 1, or it may be passed through additional separating stages before being discharged.

The form of apparatus illustrated in Fig. 5 is readily adapted to the treatment of gas at high pressure in that only the outer shell 11 and the portions of the dust delivery tubes extending therefrom need be fabricated from material heavy enough to withstand high internal pressure. Material separating units, partitions and inner housings and other parts within the outer housing 11 may be constructed of light-weight material in accordance with conventional practice since all of these parts and the compartments defined thereby are subjected to the high pressure of the gas stream. The only pressure differential existing between the various parts is that which obtains from the normal operation of the devices. The outer housing 11 is shown provided with suitable access openings 108 whereby access may be had to the interior of the housing for construction and maintenance.

Referring to Figs. 6, 7 and 8, I have illustrated a form of my invention which is generally comparable to that illustrated in Fig. 1 except that the construction has been modified to accommodate separating units having involute type gas inlets instead of vane type for producing the whirling motion of the gas. This apparatus may comprise an outer housing 111 enclosing a plurality of successive, vertically spaced separating stages G, H and I. The housing 111 may be constructed in substantially the same manner as the housing 1 of Fig. 1 and may comprise vertically aligned and connected sections 112, 113 and 114 comparable to the housing sections 2, 3 and 4 of Fig. 1. The housing 111 is further provided with a top section 115 and a bottom section not shown comparable to the sections 5 and 6 respectively of Fig. 1. The lower section 112 is provided with gas inlet means, indicated at 110, and material discharge means in accordance with Fig. 1 and the side walls of section 112 form part of stage G in the same manner that the side walls of section 2 of Fig. 1 form a part of stage A. The upper end of section 112 is provided with a conical shield 116 comparable to the shield 15 which extends across the housing 111 and defines the upper end of stage G. Gas outlet tube 116a of stage G depends from shield 116, and gas outlet opening 116b of stage G communicates with the space above the shield.

Stage H comprises an inner housing 117 provided with cylindrical side walls 118 spaced inwardly from the inner walls of the housing 111 to define a vertically extending gas passage 119 within the housing 111 around stage H. Housing 117 is also provided with a lower conical bottom wall 121 which is spaced vertically from the conical shield 116 to define therebetween an outlet header compartment 122 for the separating stage G communicating with opening 116b. The space within the compartment 117 above the conical wall 121 comprises a material collecting compartment 123 for stage H. The material collecting compartment 123 is provided at its lower end with a material delivery tube 124 comparable to the delivery tube 25 of Fig. 1, which extends downwardly through stage G to a suitable position of discharge. Housing 117 is further provided with a conical upper wall 125. Housing 117 is supported by a plurality of spaced radially extending arms 117a secured to the housing 111.

Separating stage H comprises a plurality of tubular centrifugal separating units 126 each extending into the upper housing wall 125, the wall 25 closing the spaces therebetween, and having a material discharge opening 127 communicating with the material collecting compartment 123. Each of the tubular separating units 126 is provided with gas inlet means 128 communicating 30 with the space within the housing 111 above the wall 125.

35 The gas inlet means of each of the tubular separating units is better described in connection with Figs. 7 and 8, and referring thereto, the gas inlet means 128 is shown as comprising a vertically extending wall 129 in the form of an involute spiral having a gas inlet opening 131 extending in a vertical plane. The involute section gives the gas a circular motion before it moves 40 downwardly into cylindrical portion 132 of the separating unit. This vertical wall is connected at its lower edge to the cylindrical portion 132 by transition strip 133 of tapering width. Each 45 of the tubular separating units is further provided with a short conical gas outlet tube 134 extending downwardly for a short distance through upper wall 135 of the involute section substantially concentrically of the tube 132 to prevent gas from passing directly from the inlet 50 131 to outlet opening 135 of the outlet tube 134.

In operation the gas enters the inlet opening 131, is given a whirling motion in the involute section 129 and whirls downwardly in the tube 132. Suspended material is thrown to the inner wall of the tube 132 and is discharged through the opening 127 into the collecting compartment 128. The gas then whirls upwardly through the discharge tube 134 and is discharged through the opening 135.

60 The outer housing 111 is further provided with a conical partition 137 which extends across the interior of the housing and is spaced vertically from the inlet means 128 and located adjacent the outlet means 136 of each of the units 126 and 65 is also spaced vertically from the upper wall 125 to define between this upper wall and the partition 137 a gas inlet header compartment 138 which communicates with the vertically extending passage 119. The gas outlet tubes 34 of each 70 of the units 126 extend through the partition 137 and have their discharge openings 136 communicating with the space within the housing 111 above the partition 137.

Stage I is located vertically above stage H and is
75 constructed in substantially the same manner.

Stage I is shown provided with a greater number of tubes than stage H and the tubes are of smaller diameter than the tubes shown in stage H whereby a more efficient separation of smaller particles may be obtained. Thus stage I comprises a plurality of tubular separating units 141 each having involute type gas inlet means 142 adjacent its upper end, corresponding to the inlet means 128, communicating with inlet header compartment 143 defined between an upper conical partition 144 extending across the housing 111 and upper conical wall 145 of an inner housing 146. The housing 146 is provided with cylindrical side walls 147 spaced from the inner walls of the housing 111 to define therebetween a vertically extending gas passage 148 within the housing 111 and around stage I communicating with the inlet header compartment 143. The housing 146 is further provided with conical bottom wall 149 located above the partition 137 and spaced from the inner walls of the shell 111 to define outlet header compartment 151 for stage H communicating with a vertically extending gas passage 148. The housing 146 is supported within the housing 111 through the agency of a plurality of spaced radially extending brackets 146a secured to the inner wall of housing 111.

The space within the housing 146 adjacent the conical bottom 149 defines a material collecting compartment for stage I. A dust delivery tube 153 depends from the bottom wall 149, communicates with the compartment 152 and extends downwardly through partitions 137 and 128 of stage H and concentrically within the dust delivery tube 124.

The lower end of each of the units 141 extends through the wall 148 and has a material discharge opening 154 communicating with the space within the housing 146. Each of the units 141 is provided at its upper end with a gas outlet tube 155 extending through the partition 144 and having an outlet opening 156 communicating with header space 157 defined between the partition 144 and the upper wall 115 of the housing 111. The cleaned gas may be discharged from the housing through outlet opening 158 in the upper section 115.

In general, stages H and I will have more tubular separating units than shown. In order to simplify the drawings it will be assumed that the units shown are those lying in the plane of Fig. 6. Partitions 137 and 144 are each located adjacent the outlet means of a corresponding stage and each extend completely across the interior of the housing 111, except for the openings therein through which the associated pipe and tubes extend. Thus each partition completely shuts off communication between the gas inlet and gas outlet openings of the corresponding stage, outside that stage, whereby all the gas is required to flow through each stage.

The operation of this form of my invention is substantially identical with that described in connection with Fig. 1, the only material difference being the substitution of involute-type inlets for the vane-type and the modification of the partition shapes to accommodate this type of inlet. Since the same statements in regard to the adaptability of the device to high pressure operation can be made with this form of my invention as were made in connection with Fig. 1, they will not be repeated.

It will be understood that while I have referred to the forms of my invention as being particularly suited to collection of suspended solid par-

ticles, all forms of the invention may be used without material change for the collection of suspended liquid particles.

In each of the forms of my invention, it will be noted that the housing which surrounds the separating stage forms part of the wall means defining the inlet and outlet header compartments and also part of the wall means defining the passage establishing communication between said header compartments. In this connection, it is to be noted that said header compartments are not necessarily connected by a well-defined vertically extending gas passage such as passage 28 of Fig. 1. Thus an inner housing such as a housing 146 (Fig. 6) need not have a cylindrical wall portion 147, but the top and bottom walls 145 and 149 may adjoin. Under such circumstances, the passage 148 no longer exists and the header compartments 143 and 151 are contiguous and define a passage within the housing 111 around stage I.

Having described various embodiments of my invention, it will be apparent that many changes may be made in the arrangement and location of parts without departing from the spirit and scope of my invention; and consequently, it is to be understood that I am not limited to the specific forms disclosed, but the foregoing description is to be considered as illustrative of rather than limitative upon the scope of the appended claims.

I claim:

1. In apparatus for centrifugally separating suspended material from a stream of gas, the combination which comprises: a substantially vertically extending cylindrical housing; first partition means within the housing cooperating with the lower portion of the housing to form therein a first centrifugal separator embodying a separating chamber having a centrally located gas outlet at its upper end; inlet means in the housing for delivering gas tangentially into said chamber; second and third centrifugal separators located in said housing above said partition means, the third separator being located above the second separator, said second and third separators each comprising a plurality of tubular centrifugal separating units, and each having gas inlet means and gas outlet means at its upper end, said second separator being spaced inwardly from said housing to provide a passage within the housing and around that separator for conducting gas from the gas outlet of the first separator to the gas inlet means of the second separator, said third separator being spaced inwardly from said housing to provide a passage within the housing and around that separator for conducting gas from the gas outlet means of the second separator to the gas inlet means of the third separator; a partition means corresponding to each of said second and third separator extending within the housing adjacent the gas outlet means of the corresponding separator and shutting off communication, outside that separator, between the gas inlet means and gas outlet means of that separator; and gas outlet means in the upper portion of said housing communicating with the gas outlet means of the third separator.

2. In apparatus for centrifugally separating suspended material from a stream of gas, the combination which comprises: wall means defining a substantially vertically extending cylindrical outer housing having tangential gas inlet means intermediate its ends and gas outlet means above the gas inlet means; a plurality of ver-

tically spaced partition means extending across the interior of the outer housing at positions intermediate the gas inlet and outlet means; an inner housing located between two adjacent ones of said partition means and having upper and lower wall means spaced respectively below and above the respective upper and lower ones of said adjacent partition means to respectively define inlet and outlet header compartments, said inner housing having side wall means spaced inwardly from the outer housing walls to provide communication between said header compartments; a centrifugal separator associated with said inner housing and having gas inlet means communicating with said inlet header compartment and gas outlet means communicating with the space above the upper one of said two adjacent partition means; and a gas passageway through the lowermost of said partition means communicating with the outlet header space above said lowermost partition means, the space below said partition means comprising a separator having the inner side walls of said outer housing as part of the side walls thereof, said tangential inlet being located in said side walls.

3. In apparatus for centrifugally separating suspended material from a stream of gas, the combination with a vertically extending cylindrical outer shell having a gas inlet opening and a gas outlet opening above the inlet opening, of a plurality of vertically superposed centrifugal separators entirely within the shell, each of said separators comprising a plurality of tubular centrifugal separating units each having a vertically extending central gas outlet tube provided with an outlet opening at its upper end, each of said units having an inlet opening located below its associated outlet opening, and each of said units having a material discharge opening located below its associated inlet opening; a separate material collecting hopper for each of said separators, each of said hoppers being spaced from the side wall of the shell to provide a passage for the gas stream upwardly therebetween to the inlet openings of the units of the separator with which the hopper is associated, each hopper being provided with an upper wall sealing the spaces between the units of the separator with which it is associated; and a separate partition extending across the interior of the shell above the inlet openings of each separator and sealing with the outlet tubes of the separator with which it is associated and defining with the walls of the shell an outlet header compartment with which the outlet openings of the associated outlet tubes communicate.

55

4. In apparatus for centrifugally separating suspended material from a stream of gas, the combination with a vertically extending cylindrical shell having a gas inlet opening and a gas outlet opening above the inlet opening, of a plurality of vertically spaced partitions dividing the interior of the shell into a plurality of vertically juxtaposed compartments; a separate multi-tube centrifugal separator in two adjacent ones of said compartments, each separator having gas outlet means communicating with the space in the shell above the partition defining the upper end of the compartment in which that separator is located, each separator having gas inlet means located below the partition defining the upper end of the compartment in which the stage is located, and each separator having material discharge means located below its associated gas inlet means; and a separate material collecting hopper located in each of said two adjacent compartments, communicating with the material discharge means of the corresponding separator, said hoppers being spaced from the side walls of the shell and from said partitions to provide communication from the space below each of said hoppers to the gas inlet means of the corresponding separator.
5. In apparatus for centrifugally separating suspended material from a stream of gas, the combination which comprises: a vertically extending substantially cylindrical outer housing; a first partition extending across the housing and defining part of a first centrifugal material separating means in the lower end of the housing, the lower part of the housing acting as a material receiving hopper for said separating means, said partition having an opening therethrough for the upward flow of gas discharged from said separating means; a second centrifugal material separating means located above the first separating means and having a gas outlet opening, a gas inlet opening below the outlet opening and a material discharge opening below the inlet opening; a second partition separating the gas inlet from the gas outlet opening corresponding to the second material separating means; and a material collecting hopper communicating with said material discharge opening and located in the shell above the first partition and below the gas inlet opening and spaced inwardly from the side walls of the shell to define a passage therewith for the upward flow of gas from said first-mentioned opening to said gas inlet opening.

PETER POOTJES.
